OPEN-HEARTH FURNACE

Application filed October 29, 1920. Serial No. 420,377.

Our invention relates to improvements in the structure of, and in the method of operation of, metallurgical furnaces in which continuous streams of gas are burned. We have made particular application of the invention to regenerative furnaces, and specifically to open-hearth furnaces. The objects in view are economy—economy in method, obtaining the most from the materials employed, and economy in structure, saving space and material and adhering to simplicity in form.

In the accompanying drawings furnace structure is illustrated in which and in the use of which our invention is practiced. In these drawings Fig. I is a view in horizontal section through the ports and above the hearth of an open-hearth furnace; Fig. II is a view in medial and vertical section, on the plane indicated by the line II—II in Fig. I. In Fig. II a dotted line I—I indicates approximately the plane of section of Fig. I, although it will be found that, for simplicity of illustration, Fig. I affords representation of more than any single plane of section would afford. Figs. III and IV are views in transverse and vertical section, on the planes indicated at III—III and IV—IV, respectively, Fig. 1. Fig. V is a view similar in part to Fig. I, illustrating modifications in form, and showing additionally in plan the stack connections, in connection with which a further feature of invention is found; Fig. VI is a view in vertical medial section, corresponding to Fig. II, but drawn to larger scale, and showing in this aspect the variants in structure alluded to in characterizing Fig. V.

The furnace includes the usual hearth 1 and air and gas passageways 2 and 3, duplicated at the opposite ends of the furnace. At one end of the furnace streams of air from the atmosphere and of gas from a producer advance through regenerators into passageways 2 and 3 and flow thence through suitable ports to the furnace chamber; at the opposite end of the furnace the products of combustion emerge through corresponding ports and, entering passageways 2 and 3, flow through the regenerators and thence to the stack. At suitable intervals of time the

direction of flow is reversed, so that what is first (so far as concerns these heat-affording gases) the intake end of the furnace becomes the delivery end, while the end at which the products of combustion had been escaping 55 becomes in turn the intake end.

It is in the ports through which the incoming gases flow from passageways 2 and 3 to the furnace chamber (and through which at the opposite end the products of combustion escape), where our invention centers.

It is already familiar in furnace structure to arrange the gas port on the medial line of the furnace, in the form of an arched tunnel, and to arrange the air port above and around 65 this gas port. As the drawings show, we adopt such a medial, tunnel-shaped port. It is indicated at 4. The surrounding space bears the reference numeral 5.

In the typical open-hearth furnace the 70 heated streams of air and gas are delivered separately into the furnace chamber, above the hearth; they meet for the first time there, above the hearth, and there they begin to unite, in the reaction called combustion. We 75 have departed from this, the usual practice, and have directed our efforts to effecting a mixture of air and gas immediately before delivery into the furnace chamber, and for this reason: Mixture of gas and of air within 80 the furnace chamber, being relatively uncontrolled and casual, is relatively incomplete; by special provision just before delivery to the furnace chamber, the mixing of gas and air may be controlled and made much more 85 thorough, intimate, and complete. It is true that, immediately on the mingling of these heated components, combustion begins; but, since the mixing which we effect is accomplished within a short reach of the advancing 90 streams, and immediately before delivery into the furnace chamber, the gases are delivered while the operation of combustion is at its very beginning. Stated in another way, in the usual practice, when gas and air are delivered separately into the furnace chamber, the flame springs from a point within the furnace chamber; when in the practice of our invention the air and gas are mingled just 95 before delivery into the furnace chamber, the 100

flame springs from a point slightly further back in the stream, a point within the port, just before the now burning gases emerge into the furnace chamber.

But we find there is no disadvantage in this. To the contrary, because of the relatively more thorough mixing which we achieve of the gas and the air together, combustion is much more nearly complete, the heat units available are in larger measure released within the furnace chamber, and, using gas of given composition and temperature and air of given temperature, flowing from the regenerators in given relative quantities, better heating effects can be got by following our invention than by the usual practice indicated above. The advantage of our invention may be stated in another way: by virtue of the more intimate mingling of gas and air which we effect, and the consequent more complete combustion and greater release of heat within the furnace chamber, it becomes possible for one who follows our invention to accomplish more in a furnace of given dimensions, or it may be to operate with a leaner gas, than the usual practice indicated above admits of.

Returning from this digression, and resuming the description of the structure shown in the drawings, it will be observed that the stream of heated gas, advancing from the gas regenerator, flows through passageway 3, ascends the vertical passageway 6, and, entering port 4 from the rear, sweeps through that port to the furnace hearth. The air advances in a stream from the air regenerator into passageway 2; from this passageway the now divided stream ascends through the two vertical passageways 7 and 8, and thence discharges, through the injection ducts 9 and 10, directly into the medial port 4.

A minor variation in this detail of structure is illustrated in Figs. V and VI, where the stream of gas flows from a header chamber 11 in the gas passageway through a single duct 12 into the port 4.

In both of these alternate arrangements, however, it will be noted, first, that, since port 4 is medially arranged, the instreaming flame is directed centrally into the furnace chamber; second, that the stream of air which is directed into the stream of gas to mingle with it (or the reverse), whether it approach in a single stream or in a plurality of branches, enters through leads which are symmetrically arranged, with respect to the medial vertical plane of the furnace; and, third, that the air lead (or gas lead, Figs. V and VI) approaches the port obliquely, in the direction of flow, and that the two streams consequently meet at an acute angle, and flow on with minimum deviation of course. The port is of bifurcated shape; the trunk portion opens directly to furnace hearth; the branches converge, not abruptly, but gradually, and

the general direction of flow is not seriously disturbed. The angle at which the streams meet is sufficient to effect a projection of the substances of the streams, one into the other, and this without appreciable retardation of flow.

Comparing Figs. II and VI, it will be perceived that in one case the confluent streams are disposed horizontally and in the other vertically. In open-hearth steel furnaces the former arrangement is ordinarily preferred. The substance upon which heat is to be expended is after all the pool of metal on the furnace hearth, and, as the drawings show, the port 4 is downwardly inclined, in order to project the flame upon the surface of the pool. A horizontal arrangement of the confluent streams of air and of gas gives us we find a flame which centers the heat on the pool of metal, rather than spreading it laterally to the detriment of the front and back walls of the furnace—the lateral walls relative to the line of flame projection.

It will further be noted that, beyond the point where the air enters, port 4, as shown in these drawings, flares toward the furnace chamber. Thus allowance may be made for the enlarged and now burning volume of gas. This detail is, however, a nicety of engineering, not essential to the practice of our invention in its broader aspect.

Such being the arrangement of ports and passageways, it remains to note certain features of operation which we preferably employ. These features enter into our invention, particularly when regarded as as improvement in method. At the same time, even while our invention is regarded as embodied in apparatus, these are features which preferably are employed in the use of the apparatus.

Ordinarily, in open-hearth operation, while the gas is introduced under pressure, the stream of air through air regenerator and into furnace chamber is impelled in no other manner than by the draft conditions set up by the open-hearth operation itself. No means are provided for driving the air in; it is drawn in by the furnace draft. In practicing our invention, we preferably introduce the stream of air also under pressure. For such work a blowing fan is suitable; the construction and manner of use of such fans are well known, and we have deemed it unnecessary to show a fan in the drawings. Ordinarily the gas enters the furnace from the producer under a pressure of three quarters of an inch, more or less, water gauge. We have found that pressure adequate for the gas in the practice of our invention. In correlation with such a pressure upon the gas, we preferably exert upon the air a driving pressure of an inch and a half, more or less, water gauge; that is to say, a pressure twice as great as that obtaining upon the gas. It

will be apparent to the engineer that, in consequence of the obliquity at which the air is injected into the stream of gas and in consequence of the major pressure under which the air is injected, a larger flow of gas through the port is induced than otherwise would obtain.

Recurring now to consideration of port construction, it is manifest that port 4, through which as we have said we introduce both air and gas is little larger (we preferably make it slightly larger) than the port through which ordinarily gas alone is introduced. It is in consequence of the fact that we put the air under pressure as well as the gas, that we are able to introduce through port 4 alone both the components of the combustible mixture in adequate quantities. Furthermore, in consequence of so driving the components of the mixture together through the constricted approach to the hearth and thence to the suddenly widened combustion chamber above the hearth, an intimacy of mingling of the components is achieved, utterly unrealized in ordinary practice, and with a consequent release of heat units in larger measure at the very place desired.

In the usual present-day practice, the streams of gas and of air, entering the furnace separately, mingle and burn gradually; and the result is a long and relatively speaking not so hot a flame. In following our invention, intimate mingling of gas and air is achieved before entrance into the furnace; the consequence and effect is a shorter hotter flame.

Since the pressures under which the gas and the air are introduced are variable, this important matter of length and intensity of flame is brought within the control of the operator.

Up to this point in the description we have spoken only of the air and gas entering the furnace chamber through port 4. And indeed no other or additional quantities either of air or of gas are necessary to accomplish the invention. However, varying conditions make desirable the possibility of further adaptations. The drawings show the space

50 5 extending archlike above port 4. This in ordinary structure and operation is the air port. As we have now explained, our air supply primarily enters the furnace chamber, already mingled with the gas, through port 4. Supplementary volumes of air may, however, be admitted through port 5 directly into the furnace chamber. To that end, the rising air passageways 7 and 8, through which air is fed as already described into ducts 55 9 and 10, may communicate additionally with space 5. Furthermore, dampers 13 and 14 may be provided, controlling the effective opening from passageways 7 and 8 into port 5. By adjustment of these dampers supplementary volumes of air may or may not be

admitted through port 5 to the furnace chamber, as may be desired; and, if admitted, the amounts admitted may be adjusted, relatively to the amounts of mingled air and gas advancing through port 4. This feature gives supplementary control, to the ends already indicated.

In Fig. V a further structural feature is indicated diagrammatically. It consists in a fan, located at the point 15 between the regenerators and the stack 16. Such a fan may be employed to draw the products of combustion from the furnace chamber. When used, a new factor is introduced, entering into the problem of the engineer in designing the furnace. If no such fan be contemplated, and the furnace be designed to operate in the usual manner, the area of the furnace ports will be determined, not by the volumes of entering air and gas, but by the volumes of outgoing products of combustion. These being much hotter than the entering gases are much more voluminous. As a matter of actual observation, the volume of outgoing gases is one and three quarters times that of the entering gases. It is because the port areas are made large enough to carry away the products of combustion, and under usual circumstances much larger than is needed for the supply of air and gas on the intake side of the furnace, that it becomes possible to use dampers such as 13 and 14, cutting down more or less the effective area of the ports when used for intake. But if a fan be employed, sucking the products of combustion from the furnace, the problem of designing of ports is relieved of one limitation; it will now be possible to make the ports smaller, reducing their area (if desired) even to the minimum requisite to pass the needed volumes of entering gas and air, and, in the ejection of the products of combustion, to compensate for diminution in port area by the suction of the fan.— withdrawing the gases through ports of diminished area, to be sure, but at greater velocity.

The introduction of the fan, then, into the structure, makes possible the diminution of port area; if this diminution be carried to the limit, the possibility of employing the dampers 13 and 14 is eliminated. However, given stable conditions, the ports may be properly proportioned, so that it will be quite possible to dispense with these dampers; while, on the other hand, the economies achieved in the use of a fan will justify themselves. Fig. VI shows a construction in which port 5 of the earlier figures is eliminated, and all the air enters necessarily through port 4. It will be understood from what has gone before that ordinarily a furnace so modified will have associated with it in operation a suction fan, drawing the prod-

ucts of combustion from the furnace chamber.

We have described the invention as focussed in a stream of gas impelled through a medially arranged port into the furnace chamber, with a stream or streams of air injected into the gaseous streams and mingling with the gas in a combustible mixture while the stream is still in the port, though about to pass thence into the furnace chamber. This arrangement is capable of inversion: the air may enter the medially arranged port and flow therethrough from rear to front, and the gas may be projected through the obliquely arranged duct or ducts into the advancing stream of air. The means by which this variation may conveniently be accomplished are indicated in Fig. VI. The air passageway 2 communicates with the upward leading 10 passageway 6, while the gas passageway 3 communicates with passageways 7 and 8.

The pressures under which the streams of gas and of air advance, are, in their actual and relative values, entirely under the control of the operator. Also the rate of education of the products of combustion is, if a fan be used, under the operator's control. If no fan be used, and in either case if dampers 13 and 14 be used, the effective area of the 20 ports in which they are placed is under the operator's control.

The open-hearth furnace is in some respects peculiar among regenerative furnaces. The operation which is performed within it is 25 periodic or cyclic: a charge is introduced and refined and removed and then a new charge is introduced. This condition of service presents problems very different from those found in the operation of continuous furnaces, where substantially unchanged heat 30 conditions are to be maintained throughout long intervals of time. When a charge is first introduced into an open-hearth furnace and treatment begins, an intense and relative- 40 ly short flame is most effective; as operation progresses the flame should lengthen, and finally the flame should sweep through the whole length of the hearth and disseminate as nearly as may be an even heating effect 45 throughout. Throughout all the operation, care must be taken, so to control the flame, that it shall not spread and burn the front and back walls of the furnace (the walls which, with respect to the line of flame, are 50 lateral).

Such adaptability to conditions of use is found in pressure conditions for air and for gas so established as to be under control severally and jointly, as well as in the damper- 55 controlled air passageways.

In a word, our invention affords control of intensity and of length of flame to meet conditions of cyclic operation.

In the foregoing description novelties both 60 of structure and of procedure are indicated.

It will be understood that the mode of operation is essentially that of the ordinary open-hearth furnace, modified only in respect to those matters which have been explained.

We have in the course of this specification indicated certain respects in which latitude 70 is permissible in the practice of our invention. We desire to say further in this connection that the drawings and the description here presented are exemplary. In the ensuing claims we define what is of the essence of our invention; if this be present our invention will be practiced, regardless of details of structure and procedure. As was said at the outset, the invention is applicable 75 to regenerative furnaces, and indeed generally to metallurgical furnaces into which burns a continuous stream of gaseous fuel.

We claim as our invention:

1. In a regenerative furnace, a central port 80 leading to the furnace, means for forcing regenerated air through said port, a slag pocket communicating with said port, a second slag pocket beyond said first mentioned slag pocket, a passage for fuel connecting 85 said second slag pocket and said port, an auxiliary flue connecting the first mentioned slag pocket with the furnace and acting as an out flue on the out-end of the furnace and means for closing said auxiliary flue on the in-end 90 of the furnace.

2. In a regenerative furnace, a central port 95 leading to the furnace, means for forcing regenerated air through said port, a slag pocket communicating with said port, a second slag pocket beyond said first mentioned slag 100 pocket, a passage for fuel connecting said second slag pocket and said port, an auxiliary flue on each side of said central port connecting the first mentioned slag pocket with the furnace and acting as an out flue on the out-end of the furnace and means for closing said auxiliary flues on the in-end of the 105 furnace.

3. In a regenerative furnace, a central port 110 leading to the furnace, means for forcing regenerated air through said port, a slag pocket communicating with said port through a plurality of openings, a second slag pocket beyond said first mentioned slag pocket, a passage for fuel connecting said second slag 115 pocket and said port, an auxiliary flue connecting the first mentioned slag pocket with the furnace and acting as an out flue on the out-end of the furnace and means for closing said auxiliary flue on the in-end of the furnace.

In testimony whereof we have hereunto set our hands.

ROBERT B. KERNOHAN. 125
JAMES S. LOCHHEAD.
